UNITED STATES PATENT OFFICE.

ALFRED S. DUFFIES, OF MARKESAN, WISCONSIN.

CUSHIONED WHEEL-RIM.

1,353,326.

Specification of Letters Patent. Patented Sept. 21, 1920.

Application filed February 5, 1917. Serial No. 146,598.

To all whom it may concern:

Be it known that I, ALFRED S. DUFFIES, a citizen of the United States, residing at Markesan, Green Lake county, Wisconsin, 5 have invented certain new and useful Improvements in Cushioned Wheel-Rims; and I do hereby declare the following to be a full, clear, and exact description of the invention, such as will enable others skilled in 10 the art to which it appertains to make and use the same.

My invention relates to resilient wheels of the general class employing cushions disposed in annular formation between inner 15 and outer fellys, its general objects being to provide means for excluding foreign matter from the cushions and to provide an air cushion coöperating with the annularly disposed cushions in furnishing resiliency for 20 the wheel. While my invention may be applied to resilient wheels of widely varying constructions, it is particularly adapted for use having the composite outer fellys shown in the copending applications filed by Francis Mead and myself on January 18, 1917 as 25 Serial Nos. 143046 and 143047 and I am therefore describing and picturing my invention in this illustrative embodiment.

In wheels of this type, the cushions desirably project beyond each side of one of the rims (this being preferably the inner rim) into contact with side flanges carried by the other rim, these side flanges being spaced laterally from the first named rim to 30 allow for a lateral compression of the cushions during a skidding of the wheel or other side strain upon the latter. Theoretically, it might have been expected that each lateral face of a cushion would slide upon the 35 adjacent side flange in response to the variations in the compression of the cushion at various points during each rotation of the wheel when the latter is employed on a loaded vehicle. However, I have found in practice 40 that the varying strains on the rubber cushions compress the portions disposed radially of the wheel between both of the rim portions contiguous to the cushions, and distort the projecting cushion portions without causing the lateral faces of the cushions 45 to slide upon the adjacent side flanges of the wheel. Consequently, no allowance need to be made for the texture of the lateral cushion faces, and the interposing of fabric be-

tween each such face and the adjacent side 55 flange would not alter the action of the cushion. However, the spacing of each side flange from the other felly affords an opening for the admitting of dirt, stones, slush and other materials which may considerably 60 reduce the life of the cushions if admitted where they might enter any spaces between the cushions and adjoining wheel parts. My invention aims to exclude all such foreign materials from the annular chamber housing 65 the cushioning elements, by providing flexible curtaining extending inwardly of the wheel at both sides of the latter, and by securing this curtaining to both fellys in such a manner as to afford a water-tight 70 chamber. My invention also aims to use curtaining for this purpose which will be airtight, and to inflate the resulting chamber so as to afford a pneumatic tube housing 75 the cushioning elements and coöperating with the resiliency of the latter to cushion the wheel, so that the latter will ride partly upon the rubber cushions and partly upon the compressed air.

Figure 1 is a fragmentary side elevation 80 of a wheel embodying my invention.

Figs. 2 and 3 are enlarged transverse sections of rim portions of such wheels, showing alternative methods of securing the fabric to the inner felly. 85

Fig. 4 is a fragmentary side elevation of a wheel having the rim portions shown sectionally in Fig. 2.

Fig. 5 is a fragmentary interior view of the annular channel formed by the angle-sectioned rim portions and the flexible fabric of Fig. 2. 90

In the embodiments of the drawings, the wheel in each case includes spokes 1 fast upon an inner felly 2 (desirably of wood), which felly has a steel band 3 upon its periphery. Spaced radially from this band is a steel rim forming part of the outer felly and fast with respect to both the tread 4 and the side flanges 5 and 6. This band may be a single element 7 integral with the side flange 6 as in Fig. 3, in which case the other flange 5 may be integral with the steel rim 8 which is shrunk upon the band 7 and which carries the tread 4. Or, the said band may consist of laterally adjacent portions 9 and 10, as in Fig. 2, and may be secured to the tread-carrying rim 11 by the 95 100 105

wedging of a cylindrical member 12 (such as a standard "S. A. E. band") between this member and the two portions 9 and 10, each of which latter portions has one of the side flanges integral with it.

Interposed between the inner felly band 3 and the said outer band (which latter is either the single element 7 or a composite of the separate portions 9 and 10) are the cushioning means, desirably consisting of rubber cushions 11 disposed in two annular formations spaced by a web 12 on the inner band 3. These cushions project laterally beyond the inner felly and bear with their lateral faces tightly against a flexible fabric 13, which fabric desirably consists of an annular and inwardly open channel interposed between the cushions and the said outer band. Both edges of the channel-faced fabric are tightly secured to the inner felly, and desirably to the inner surface of the latter. For example, in Figs. 2 and 4, each edge portion of the fabric is lapped over the inner surface of the felly 2 and socketed in a groove in this felly, being normally held in this groove by a steel split ring 14. Or, the felly 2 may carry an inwardly directed clencher rim 15 interlocking with clencher formations 16 on the edges of the fabric. In either case, it will be obvious from Figs. 2 and 3 that the fabric co-operates with the inner felly 2 to form an annular chamber inclosing the cushions and the inner band 3 upon which the cushions slide peripherally to some extent when the wheel is in service, thus excluding all foreign matter from these portions. To make this housing still more effective, I preferably provide a valve 17 on the inner felly, connected to a passage 18 leading to the interior of the said chamber, so that air may be pumped into this chamber to cause the fabric to bulge out somewhat and to provide the equivalent of a pneumatic tube between the two fellies of the wheel. Thus constituted, the fabric affords both a mechanical protection to the cushions against the impact of stones or the like, a jacketing to exclude mud and grit from the cushioning, and a pneumatic cush-

ion co-operating with the rubber cushions 50 for affording resiliency to the wheel. In practice, the thickness of the required fabric is quite small, so that the use of the same enables me to reduce the thickness of the cushioning needed for the same total resiliency, 55 thereby permitting the spokes to be lengthened and the wheel to be lightened.

For the embodiments here illustrated, the fabric is desirably made of a reinforced rubber, such as that commonly used for outer 60 tire casings, but with the reinforcing so disposed that the edge portions of the fabric can be stretched somewhat. Then either side of the fabric can be bent outwardly when desired, as in the case of Fig. 2 where 65 the dotted lines show the position of a portion of the fabric before the left-hand rim portion comprising the elements 5 and 9 is forced into its normal position. Where the cushions in each annular formation are 70 separate elements spaced by transverse webs 19 and 20 on the inner and outer rim members, I preferably mold the fabric with outwardly open pockets 21 designed to fit over the webs 20. However, I do not wish to be 75 limited to this or other details of the construction and arrangement here described, it being obvious that the same may be modified in many ways without departing from the 80 spirit of my invention as claimed.

I claim as my invention:

1. In a wheel, an inner and an outer rim, a cushion therebetween, and a single-piece fabric member including side portions disposed at opposite sides of the cushion, and 85 a central portion clamped between the cushion and one of the rims, the said member co-operating with the other rim to form an inflatable housing for the cushion.

2. In a wheel, an inner and an outer rim, 90 a cushion therebetween, and an airtight flexible element clamped between the cushion and one of the rims, and extending laterally past the cushion at opposite sides of the latter, said element being secured at both 95 edges to the other rim.

Signed at Chicago, January 31, 1917.

ALFRED S. DUFFIES.
